UNITED STATES PATENT OFFICE.

WILLIAM A. ESTAVER, OF CAMBRIDGE, MASSACHUSETTS.

FRINGING ATTACHMENT FOR SEWING-MACHINES.

SPECIFICATION forming part of Letters Patent No. 251,852, dated January 3, 1882.

Application filed November 19, 1881. (No model.)

To all whom it may concern:

Be it known that I, WILLIAM A. ESTAVER, of Cambridge, in the county of Middlesex and State of Massachusetts, have invented an Improvement in Sewing-Machines, of which the following description, in connection with the accompanying drawings, is a specification.

This invention has for its object the production of a sewing-machine attachment for the manufacture of fringe.

I have herein shown my invention applied to a Willcox & Gibbs sewing-machine; but it may be applied with but slight modification to other well-known sewing-machines.

In this my invention, wherever a fringe is to be formed upon the cloth or other material from a thread of wool, silk, or cotton, I employ in front of the presser-foot a vibrating thread-guide, which, in its movements at right angles, or thereabout, to the direction of the feed movement of the material, has the fringing-thread carried by it caught by a fringing-hook, which hook holds the fringing-thread and carries it under the presser while the thread-carrier is moved past the opposite side of the presser, and on reaching its farthest outward position a heading-finger engages the fringing-thread near the thread-guide and carries it forward under the presser, so that the needle in its next descent will cross the needle-thread over and stitch the fringing-thread down upon the material. The head of the fringe is laid by the heading-finger. The heading-finger and the adjustable fringing-hook are herein shown as carried by the same shaft.

I am aware that fringe has been formed upon fabrics on a sewing-machine, but not by mechanism constructed as herein shown.

Figure 1 represents in front elevation a sewing-machine having my fringing attachment applied to it; Fig. 2, a front view thereof; Fig. 3, a front elevation of part of the machine with the thread-guide and its co-operating devices in a different position; Fig. 4, a sectional detail on the dotted line *x*, Fig. 3. Fig. 5 represents fringe such as made by my attachment; and Fig. 6, a sectional detail on the line *y*, Fig. 3.

The drawings represent a regular Willcox & Gibbs sewing-machine, *a* being the needle-bar; *a'*, the vibrating arm to reciprocate the needle-bar and its attached eye pointed needle; *a''*, the

usual hook-shaft; *a³*, the hook; *a⁴*, the usual four-motioned under-feeding device; *a⁵*, the usual presser-foot bar, and *a⁶* the work or cloth support. 55

The frame *b* of the fringing attachment, adjustably connected with the work-support by a thumb-screw, *c*, has bearings which receive the rocker-shaft *b'*, provided at one end with the arm *b²*, slotted, as shown in Fig. 6, to permit the connection with it at a point more or less distant from the shaft *b'* of the link *d*, which embraces the eccentric *d'* on hook-shaft *a²*, the connection between the said link and arm *b²* being made by a thumb nut and screw, *c²* *c³*. When the upper end of the link is connected with the arm *b²* nearest the shaft *b'* the eccentric *d'* gives to the rock-shaft its greatest movement to lengthen the fringe. The rock-shaft *b'* has fixed to its front end the heading-finger *e*, and outside one of the bearings of the frame *b* the said rock-shaft has adjustably connected with it by the screw *2* the fringing-hook *f*, having a hooked point, *f²*. The fringing-hook may be adjusted to place its point more or less back of the heading-hook, to thus determine the length of the loops of the fringe *g* to be formed on the cloth or other material, *h*, as in Fig. 5. 70 75 80

The thread-carrier is composed of a lever, *i*, pivoted at *i⁵*, slotted at *i³* to receive a stud or roller, *i⁴*, on the vibrating arm *a'*, by which to vibrate the said thread-carrier, and of a delivery-piece, *i²*, detachably connected with the main part of the thread-carrier by a screw, *i³*.

The thread to be used for the fringe *g* will be led through the eye *4* in the spring take-up *k*, and thence into and through the eye *5* of the delivery-piece *i²*, and then to the cloth or material *h*. The presser-foot *l* is extended at its inner side toward the fringing-hook, to bear on and prevent the loops of fringe from rising or curling up in the way of the needle. When the thread-guide is in the position shown in Fig. 3 the fringing-hook comes into its most forward position toward the operator, and as the thread-guide is moved to its position shown in Fig. 1 the fringing-hook engages its thread and is moved backward more or less, according to the throw of the rock-shaft *b'* and the position of hook *f* thereon. As the hook *f* is moved backward into its position, as in Fig. 2, it holds onto the loop of fringe at the point 90 95 100

10, draws one part, 12, thereof fully under the presser-foot, and the other part, 14, but partially under the presser-foot. Just before the thread-guide reaches its farthest position to 5 the left, as in Fig. 1, and the hook *f* its farthest position to the rear, the heading-finger *e* engages the fringing-thread near the thread-guide and is moved backward from the operator, carrying the portion 14 of the loop 10 of fringe being formed back under the presser-foot, holding the said portion near the outer side of the presser-foot and stretched under the presser-foot between the said finger and the hook *f*, thus measuring off and holding the 15 thread in a loop of the desired length, while the regular needle of the needle-bar *a*, properly supplied with thread, descends and crosses its thread over both portions 12 14 of the loop, making a stitch, 13, and making the head of 20 the fringe *g* on the material *h*.

This inexpensive and simple attachment may be quickly and easily applied to a sewing-machine, and be made to produce a fringe of greater or less length.

25 I claim—

1. The thread-guide *i*, combined with the fringing-hook *f* and heading-finger, to carry the fringing-thread backward under the presser-foot to be stitched in place, substantially as described.

2. The rocker-shaft, its arm, and link *d*, adjustably attached to it, and the fringing-hook and heading-finger carried by the said rock-shaft, combined with the thread-guide, the needle, needle-bar, and presser-foot, under 35 which the fringing-thread is drawn, substantially as described.

3. The rock-shaft *b'*, bearings for it, and means to rock it, combined with the heading-finger and fringing-hook carried by the said rock-shaft, and made adjustable thereon relatively each to the other, substantially as described.

In testimony whereof I have signed my name to this specification in the presence of two subscribing witnesses.

WILLIAM A. ESTAVER.
